BAG FEEDING APPARATUS

Robert P. Eagles, Richmond, Va., assignor to
Virginia-Carolina Chemical Corporation, Rich-
mond, Va., a corporation of Virginia

Application November 4, 1946, Serial No. 707,591

8 Claims. (Cl. 223—39)

1

In spite of the fact that automatic bag feeding mechanism for bag turning machines is described in the prior art it has been my experience that it is not commonly used and that the bags usually are fed to the turning machines by hand. This is very tiring work and is a frequent cause of occupational disability.

An object of my invention is to provide a simple and practical automatic bag feeding mechanism which readily may be incorporated into existing bag turning machines.

In reducing my invention to practice, I have incorporated my bag feeding mechanism into a so-called Ersted bag turning machine, making only such alterations therein as were necessary to effect the combination. It will be understood from the following disclosure of the invention that my bag feeding mechanism may be incorporated into or combined with any bag turning machine of the type in which the mouth of the bag is placed over and held by holding fingers while it is being turned.

In the accompanying drawings I have illustrated my bag feeding mechanism in combination with the so-called Ersted bag turning machine.

Referring to the drawings:

Fig. 1 is a side elevation of the machine, the bag feeding mechanism being in position to pick up a bag.

Fig. 2 is a perspective view of the cam shaft which operates the movable parts of the bag feed mechanism with the driven sprocket wheel which turns the shaft omitted.

Fig. 3 is an enlarged detail side elevation of a portion only of the machine showing the bag feeding mechanism in the position at which the mouth of the bag has been drawn over the holding fingers.

Fig. 4 is an enlarged side elevation of a portion of the machine showing the bag feeding mechanism in the position at which it has released the bag and is ready to move forward to pick up another bag.

Fig. 5 is a plan view of a portion of the machine, the showing being confined to the parts shown in elevation in Figs. 3 and 4.

Fig. 6 is an enlarged sectional view of the pick up head of the bag feeding mechanism.

Fig. 7 is a section taken on the line 7—7 of Fig. 5, certain parts being shown in elevation.

Fig. 8 is a view, partly in elevation and partly in section, of one of the pick up members as viewed on the section line 8—8 of Fig. 7 and

Fig. 9 is a section taken on the line 9—9 of Fig. 8.

2

The bag turning machine to which my bag feeding mechanism has been applied consists essentially of the frame 1, the pressure rolls 2, which receive the turned bag and deliver it to the piling device 3, the receiving fingers 4, which open and hold the mouth of the bag while it is being turned, the pressure bar 5, which cooperates with the lower fingers to hold the bag firmly while it is being turned, the platform 6, the turning sticks 7, and operating mechanism for driving the rolls 2, and moving the fingers 4, and the sticks 7, including the main drive shaft 8. The showing of the means for operating the fingers 4 has been omitted so that the bag feeding mechanism can be more clearly seen. The shaft 8 drives the cam shaft 9 through the sprocket wheel 10, chain 11 and another sprocket wheel 12 on the shaft 9.

The shaft 9 carries the three cams 13, 14 and 15. Cam 14 rotates in contact with the roller 16 on the end of arm 17 to turn the shaft 18 and oscillate the arms 19. Cam 13 rotates in contact with the roller 20 on the lever 21 which oscillates the link 22 and arm 23 secured to the shaft 24 and thus oscillates the pick up members 25. The cam 15 rotates in contact with the roller 26 carried on the arm 27, movement of which operates the valve 28 which controls the suction transmitted through the flexible hose 29 to the pick up members 25.

30 By means of the mechanism described above it will be seen that the pick up members 25 are moved first forwardly and downwardly into contact with the uppermost of a pile of bags on the support 6 and then rearwardly and upwardly to lift and move the open end of the bag over the ends of the fingers 4. It is noted that in the position shown in Fig. 1 the fingers 4 are closed and their ends elevated to receive the bag. In the position shown in Fig. 4 the fingers 4 have been spread apart to open the mouth of the bag and also moved downwardly so as to position the bag in the path of the turning sticks 7.

The pick up members 25 are carried by the shaft 24. This shaft is square in cross section excepting at the end cylindrical bearing surfaces 30 which fit within the journaled ends of the arms 19. The arm 23 is secured to one end of the shaft 24 by the key 31. The shaft 24 is tubular and contains the shaft 32 turnably secured therein by the set screw 33 fitting into the groove 34. The shaft 32 has oppositely screw threaded portions 35 and 36 and the projecting square end 37 for turning it. The tubular shaft 24 is provided along one side thereof with a longitudinal slot 38 which extends over the threaded portions 35 and 36 of the

shaft 32. Square openings in the hub ends of the pick up members 25 fit over the shaft 24 and may be tightened thereon by the set screws 39 and the blocks 40. The hubs of the pick up members carry the split nuts 41, held in position by the bolts 42, which slidably fit the groove 38 in the shaft 24 and engage the screw threaded portions 35 and 36 of the shaft 32. Thus the pick up members 25 may be moved farther apart or closer together to accommodate bags of different widths. The fingers 4 are similarly adjustable but since this feature constitutes no part of the present invention it has not been illustrated.

Each pick up member 25 comprises the hub portion above referred to, a tubular portion 43 projecting therefrom, a shaft portion 44 and the pick up head comprising toothed whirls 48 and 49. One end of the shaft portion 44 fits within the tubular portion 43 against the spring 45 and is secured by the bolt 46 which extends through the elongated opening 47. The other end of the shaft portion 44 provides a partial housing and support for the toothed wheels 48 and 49. The axle 50 of wheel 49 is connected to the arm 51 which is in turn connected to the piston rod 52. Piston 53 is reciprocated in the cylinder 54 by successively decreasing and increasing the air pressure in the cylinder 54 through the hose 29. The teeth of wheel 48 engage the teeth of wheel 49 so that when wheel 49 is turned in one direction wheel 48 is turned in the opposite direction.

The operation of the apparatus is as follows: A workman places a stack of bags 55 on the platform 6 and starts the machine. The cams 13, 14 and 15 are so positioned on the shaft 9 that the pick up members 25 will first be moved to the position shown in Fig. 1 with the toothed wheels 48 and 49 in contact with the top-most bag, the cam 15 then operates the valve 28 to apply suction through the hose 29 to the cylinder 54 which raises the piston 53 and connecting rod 52 and rotates the arm 51, the shaft 50 and the wheels 48 and 49 to pinch up the top layer of cloth as shown in Fig. 6. The cam 14 then operates to raise and swing the pick up members 25 rearwardly and then the cam 13 operates to swing the pick up members 25 rearwardly to the position shown in Fig. 3. At this point, the cam 15 operates to release the suction and permit the piston 53 to return to its original position, rotate the toothed wheels 48 and 49 and release the bag. In the meantime the fingers 4 have opened and moved downwardly and the reversing rods 7 have moved to turn the bag as shown in Fig. 4. The bag is then caught by the rolls 2 and discharged and the operations described are repeated.

As will be apparent the piston 53 may be operated by superatmospheric pressure rather than by suction and means for moving it positively in both directions to pick up and release a bag may be provided without departing from my invention.

It is noted that the springs 45 in the pick up members permit the latter to contact the bags with the proper amount of pressure for the best operation of the toothed wheels 48 and 49 in picking up only the top layer of cloth over a considerable range of thickness of the pile of bags on the platform 6. It is understood that the size and shape of the teeth on the wheels 48 and 49, the tension of the springs 45 and even the extent of movement of the piston 53 may be varied for picking up different kinds of bag ma-

terial, i. e. smooth or rough or thick or thin or stiff or flexible cloth. It is understood also that the cams 13, 14 and 15 must be adjusted to obtain the proper sequence of movements and the bag pick up mechanism must be timed to cooperate with the bag holding and turning mechanism, all of these adjustments being within the skill of a mechanic.

The bag pick up mechanism gives a more accurate placing of the bags on the fingers 4 than is possible by manual operation and moreover makes possible a more rapid and continuous operation of the bag turning machine. A workman attending the machine has only to supply it with bags to be turned and to start and stop it and is relieved of the tension involved in rapidly and continuously feeding the bags to the turning mechanism by hand.

1. Claim:

1. Apparatus for picking up and transporting a single layer of fabric from the top of a pile of layers of fabric comprising an upwardly extending arm pivoted at a point remote from its upper end, a downwardly extending arm the upper end of which is pivotally supported adjacent the upper end of the first named arm, a pick up head at the lower end of said second named arm, means for periodically swinging said first named arm about its pivot point to move the upper end thereof back and forth through an arc, means for periodically swinging said second named arm back and forth about its pivot point and means for periodically operating said pick up head to pick up and release a layer of fabric.

2. Apparatus as defined in claim 1 in which the upwardly extending arm is secured adjacent its lower end to a rotatable shaft and in which the means for swinging said arm comprises a second arm secured to said shaft and a cam engaging said second arm.

3. Apparatus as defined in claim 1 in which said downwardly extending arm is secured at its upper end to a shaft which is rotatably supported by the upper end of the upwardly extending arm and the means for swinging said downwardly extending arm comprises a second arm secured to the rotatable shaft supported by the upper end of said upwardly extending arm, a lever pivoted at a fixed point, a link connecting a point on said lever and a point on said second arm secured to said shaft supported by said upwardly extending arm, and a cam engaging said lever.

4. Apparatus as defined in claim 1 in which said downwardly extending arm comprises a hub portion and a shaft portion which is movable endwise with respect to said hub portion and resilient means urging said shaft portion away from said hub portion but permitting movement thereof in the opposite direction.

5. Apparatus as defined in claim 1 in which the pick up head comprises two rotatable toothed wheels engaged to rotate in opposite directions.

6. Apparatus as defined in claim 1 in which the pick up head comprises two rotatable toothed wheels engaged to rotate in opposite directions and means for operating said head comprises means for periodically rotating said toothed wheels.

7. Apparatus as defined in claim 1 in which the pick up head comprises engaged rotatable toothed wheels and the means for operating said pick up head comprises an arm secured to the axle of one of said wheels, a piston connected

to said arm, a cylinder enclosing said piston and means for periodically altering the pressure in said cylinder.

8. Apparatus as defined in claim 1 comprising a rotatable shaft carrying three cams, one for swinging said upwardly extending arm, one for swinging said downwardly extending arm and one for operating said pick up head.
